UNITED STATES PATENT OFFICE.

OSCAR SUNDT, OF CLEVELAND, OHIO, ASSIGNOR TO THE GARRETT-CROMWELL ENGINEERING COMPANY, OF CLEVELAND, OHIO, A CORPORATION OF OHIO.

POWER-DRIVEN ROLLER-TABLE.

CIFICATION forming part of Letters Patent No. 714,758, dated December 2, 1902.

Application filed February 1, 1902. Serial No. 92,159. (No model.)

hom it may concern:

own that I, OSCAR SUNDT, of Cle-
ahoga county, Ohio, have invented
useful Power-Driven Roller-Ta-
ich the following is a full, clear, and
cription, reference being had to the
y drawings, forming part of this
on, in which—

1 is a side elevation showing a por-
the roller-table constructed in ac-
with my invention. Fig. 2 is a simi-
a larger scale, partly in section,
partial transverse section; and Fig.
plan view showing a modified form
aratus for roller-tables used for stiff
uch as bars, rails, &c.

vention relates to the driving of the
feed-tables for rolling-mills, and is
to provide a simple, cheap, and
aged system for such purpose.
vention consists, essentially, in pro-
draulic turbines upon the project-
of the rollers, which turbines are
by valved supply-pipes with a
iquid under pressure.

er consists in providing eduction-
the turbines, which convey the liq-
ack to the source of supply, so that
circuit of the motive liquid is pro-

onists in providing step-down gear-
en the turbines and the rolls as
the construction and arrangement
rts, as hereinafter more fully de-
d claimed.

rawings, referring to the forms of
and 3, I show a table arranged to
at the delivery end of a hoop-mill,
le is designed to draw the hoop for-
prevent kinking and scrapping.
n the table as provided with rollers
d in bearings 3, the shafts 4 of the
jecting through the bearings at one
carrying small turbine-wheels 5.
ine-wheels are provided with suit-
gs 6, which are preferably provided
removable covers 7. The hy-
upply-pipe 8 leads from a centri-
9 in the form shown, and from this
upply-pipe the valved branches 10

lead into the turbine-casings and are arranged
to deliver the fluid to the turbines at the
proper point. Each casing is provided with
an outlet-pipe 11, these pipes leading to a
common return-pipe 12, which extends to the 55
entrance feed-opening of the centrifugal
pump. I have shown the rollers as spaced a
considerable distance apart, with guide-plates
13 arranged between them; but the number,
size, and arrangement of the rollers may be 60
varied widely within the scope of the inven-
tion. Instead of the centrifugal pump shown
I may use a reservoir, into which the exhaust
liquid is pumped and from which it is fed to
the turbines.

For using the system upon ordinary feed-
tables the turbines would give too high a
speed to be practicable, and for such tables
I use step-down gearing between the turbines
and the rollers. Thus in Fig. 4 I show the 70
protruding shaft of the roller as provided
with a worm-wheel 14, intermeshing with a
worm 15 on a shaft extending parallel with
the axis of the table and to which shaft is
secured the turbine-wheel 5' within the cas-
ing 6'. The feed and exhaust pipes are ar-
ranged as in the first form; and the system is
thus made applicable to ordinary feed-tables
used for the supporting and conveying of
rolled material.

The advantages of the invention result from
the use of the liquid in connection with tur-
bines, from the valved individual supply-
pipes, and the continuous circuit of the liq-
uid. A simple, compact, and cheap system 85
is thus afforded by which the rolls may be
driven at high speed, or at lower speed when
the intermediate gearing is used.

Many variations may be made in the form
and arrangement of the rolls, the source of 90
liquid-supply, &c., without departing from
my invention.

I claim—

1. A rolling-mill feed-table having a set of
rollers, a set of driving-turbines, each con- 95
nected to a single roller, and a source of liq-
uid under pressure having valved supply-
pipes leading to the turbines; substantially
as described.

2. A rolling-mill feed-table having a set of 100

turbines each having an actuating connection with a single roller of the table, a source of fluid-supply having valved connections to the turbines, and exhaust connections leading to the source of supply; substantially as described.

3. A rolling-mill feed-table having turbine-driven rollers, a source of fluid under pressure having a pipe extending along the turbines, valved branches leading from the supply-pipe to the turbines, exhaust-pipes leading from the turbines to a common return-pipe, and means for forcing the fluid back to the source of supply; substantially as described.

4. A rolling-mill feed-table having rollers, each roller having an individual actuating-turbine connected therewith by slow-motion gearing; substantially as described.

5. A rolling-mill feed-table having rollers, turbines connected with the rollers by slow-motion gearing, and mechanism for forcing the fluid in an endless circuit to and from the individual turbines; substantially as described.

6. A rolling-mill feed-table having a set of rollers, a set of driving-motors, each connected to a single roller, and means for varying the speed of each motor; substantially as described.

In testimony whereof I have hereunto set my hand.

OSCAR SUNDT.
